PORTABLE DISPLAY RACK

Filed Dec. 17, 1928

INVENTOR,
Charles R. Seltzer;
Harry W. Bowen.
ATTORNEY.

UNITED STATES PATENT OFFICE

CHARLES R. SELTZER, OF LONGMEADOW, MASSACHUSETTS

PORTABLE DISPLAY RACK

Application filed December 17, 1928. Serial No. 326,544.

This invention relates to improvements in portable display racks for oils, greases and other articles.

The present invention is an improvement over that shown, described and claimed in my pending application for Letters Patent of the United States, filed October 31, 1928, bearing Serial Number 316,249, for Portable display racks. In my prior application, was shown a wheel supported structure having two upwardly extending side bar members between which are pivotally mounted a series of swinging shelves and at the bottom portion of the side members is located a fixed shelf having fixed partitions. The swinging shelves were provided with removable racks for accommodating containers of different sizes and shapes, as rectangular or circular.

The present invention is confined to the construction of the fixed shelf at the lower ends of the side bar members and this shelf is formed with an upwardly extending support having curved recesses for retaining in place circular shaped containers of different sizes, when placed on the fixed shelf, whereby circular shaped containers may be supported therein against displacement.

Referring to the drawings:

Fig. 1 is a side elevational view of the lower portion of the supporting frame and one of the supporting wheels.

Fig. 2 is an enlarged view of the fixed shelf removed from its supporting frame and illustrating the recessed rack member therein.

Fig. 3 is a plan view looking downward into the fixed shelf showing the plate having curved recesses for receiving circular shaped containers.

Referring to the drawings in detail:

1 designates one of the supporting wheels. 2, the axle member, 3 the rear brace which extends from the axle 2 to the inclined side members 4. 5 is a brace bar extending from the bar 3 forward for retaining the display rack in a stable and slightly inclined position, its lower end 5' resting upon the floor line, as shown. The bar 5 is secured to the members 3 and 4 with the bolts or rivets 6 and 7. 8 designates as a whole the fixed shelf which is secured to the member 4 by the rivet

9 and the bolt or rivet 7 which secures the bar members, 4 and 5, together, the securing means passing through the openings 10 and 11 in the end members 22 of the shelf. The rear wall 12 of the fixed shelf extends upward a greater distance than the forward wall 13. Secured to the bottom 14 is an upwardly extending flexible standard composed of two (2) pieces of sheet metal indicated at 15 and 16. These are placed close together and their bent portions 17 and 18 are riveted to the bottom 14, as shown at 15'. Their upper ends are bent outwardly in opposite directions, as shown at 16 and 17 and these edges are formed with cutout or recessed portions 18 and 19, preferably curved, as shown in the plan view of Fig. 3. These pieces form a support for retaining the oil or grease containers in an upright position, as they enter recesses 18 and 19, as shown in dotted lines at 20 and 20'.

For the purpose of firmly holding the containers in place, the front wall portion 13 is carried upward and bent downwardly and inwardly into the fixed shelf to an elastic edge 21 against which the container 20 rests. In other words, the part 21 is a springy or yieldable member for the container 20. The walls 12 and 13 are retained in place by means of the upwardly bent end walls 22 and the inwardly bent ends 23 and 24. 25 are rivets for connecting these ends to the end walls 22 and to the front and rear walls 12 and 13.

26 illustrates one of the swinging shelves which is shown in my prior referred to application, which shelf is pivotally connected to the side bars 4. No claim is made to this construction in this application.

When a can or container 20 or 20' is placed on the bottom of the shelf and located in one of the recesses 18 or 19, and against the elastic edge 21 and the bendable members 15 and 16, the container will be held in a firm or clamped manner on the shelf 8. It is obvious that the members 15 and 16 will yield or bend in opposite directions and therefore the cans are firmly secured in place.

What I claim is:

1. A display rack for containers, having, in combination, a framework, a shelf with side portions secured to the framework, the

shelf having upwardly extending bendable means between the side portions for retaining a container against movement and in a fixed position, said means comprising a pair of substantially U-shaped members that are secured to the bottom portion of the shelf and their upper ends being bent outwardly in opposite direction and having recesses formed in their edges, as described.

10 2. In a structure for display purposes, a support therefor, a shelf secured to the support and having upwardly extending sides, flexible means on the shelf having oppositely extending portions and recesses in said portions, into which containers are placed, and in engagement with the sides of the shelf for securing the same against displacement.

15 3. A shelf designed to be secured to a supporting structure, the shelf having front and rear walls, a bendable member located on the shelf and secured to the bottom thereof, said member comprising U-shaped pieces placed in juxtaposition, their upper edges having recesses, whereby, when containers are located 20 in the recesses, they will be prevented from becoming displaced.

25 4. A shelf for the purpose described comprising front and rear walls, the front wall having an inwardly bent edge portion extending into the shelf for providing a flexible abutment to retain an article against displacement, the shelf having recesses into 30 which the article to be displayed on the shelf is placed, the recesses and the flexible wall 35 co-operating to engage the front and rear walls of containers to be displayed.

In witness whereof, I have hereunto affixed
by signature.

CHARLES R. SELTZER.
